(57) **CLAIM**

The ornamental design for a combination wristband label form with tags, as shown and described.

DESCRIPTION

FIG. 1 is a front view of a combination wristband label form with tags showing the new design; and, FIG. 2 is a back view of the combination wristband label form with tags of FIG. 1.

The dash-dot-dot-dash lines showing the bottom grid and two outermost rounded rectangles in FIG. 1, and the outline of the wristbands and the outline of the tags in FIG. 2 illustrate die cuts that form part of the claimed design. The dash-dot-dot-dash lines showing the two innermost rounded rectangles in FIG. 1 demarcate openings, through which another layer of the combination wristband label form with tags is visible, that form no part of the claimed design. The dash-dot-dot-dash lines showing the horizontal lines in FIGS. 1 and 2 illustrate perforations that form no part of the claimed design. The dashed lines shown in FIGS. 1 and 2 depict portions of the combination wristband label form with tags that form no part of the claimed design.
